US0D1083979S

(12) **United States Design Patent** (10) **Patent No.:** **US D1,083,979 S**
Varga et al. (45) **Date of Patent:** **** Jul. 15, 2025**

(54) **DISPLAY SCREEN WITH A GRAPHICAL USER INTERFACE**

(71) Applicant: **ZOLL MEDICAL CORPORATION**, Chelmsford, MA (US)

(72) Inventors: **Christopher M. Varga**, Laguna Hills, CA (US); **Terry Blansfield**, Orange, CA (US)

(73) Assignee: **ZOLL MEDICAL CORPORATION**, Chelmsford, MA (US)

(**) Term: **15 Years**

(21) Appl. No.: **29/888,035**

(22) Filed: **Mar. 27, 2023**

Related U.S. Application Data

(60) Continuation of application No. 29/786,190, filed on May 28, 2021, now Pat. No. Des. 982,024, which is a division of application No. 29/686,370, filed on Apr. 3, 2019, now Pat. No. Des. 921,034.
